FASTENING-INSERTING MACHINE

John T. Lancaster, Newton, Mass., assignor to
United Shoe Machinery Corporation, Flem-
ington, N. J., a corporation of New Jersey

Application August 29, 1940, Serial No. 354,731

88 Claims. (Cl. 12—42)

This invention relates to machines for inserting fastenings in work-pieces, it being herein disclosed in connection with the attachment of a heel to a shoe by a screw driven through the heel-seat of the shoe into the applied heel.

A well-recognized practice in shoemaking is to include in the means for fastening a heel to a shoe a screw, which is inserted in a hole drilled through the heel-seat into the heel. This screw may be temporary, it being removed after an attaching adhesive has set, or may be permanent, becoming part of the finished shoe. While the present invention is applicable to either purpose, it has some features which render it especially useful for the insertion of a temporary screw, this occurring through a passage in a last within a shoe. Its object is to minimize the time required for the operation, to relieve the operator of effort and to effect secure and accurate attachment with work differing in character.

In the attainment of this object, as a feature of the invention, I combine with means which operates to form a hole in work carried by a movable support, as by a drill, and to insert a fastening in the formed hole, as by a screw-driver, means acting under the power of the machine for moving the support to present the work to the operating means at different stations and hold it for the successive formation of the hole and the insertion of the fastening. The operating means, or drilling and inserting tools, are also preferably moved under power to determine their time of operation. In the illustrative embodiment of the invention, there is a rotary and reciprocating drill and a rotary and reciprocating screw-driver or fastening-inserting device, while a support, which initially positions the work to receive the action of the drill, is under the influence of means which moves it to receive the action of the inserting device, and then returns it by reverse movement to its position at the drill. With the support at the inserting position, the inserting device may be retained temporarily in its inserting relation to receive the succeeding fastening, and then retracted before the return of the support. While the support is at its initial position, the drill, or other tool, is preferably advanced through a portion only of its operating movement and then stopped to permit the application thereto of a last-passage, serving as a gage for the work, its operating advance thereafter being completed. In many respects, my improved machine is particularly adapted for operating upon lasted shoes, the drilling and screw-inserting operations taking place through a passage in the last.

Other features of the invention are concerned with the mounting of the drilling and screw-inserting mechanisms together upon a secondary frame, for ready application to and removal from the main frame; adjustments to compensate for different positions of the work upon its support, as for different heights of lasts and for different angular relations of the last-passages; means for clamping the heel upon the heel-seat of the shoe; the manner of shifting the work-support between the two operating positions; means for obtaining a divided operating cycle; mechanisms for rotating and reciprocating the drill and screw-driver; and the arrangement of screw-holding fingers associated with the screw-driver.

In the accompanying drawings,

Fig. 1 shows my improved fastening-inserting machine in side elevation, with parts broken away;

20 Fig. 2 is a broken top plan view;

Fig. 3, a vertical sectional detail on the line III—III of Fig. 2;

Fig. 4, a front elevation of the upper portion of the machine;

25 Fig. 5, a vertical sectional detail on the line V—V of Fig. 2, showing the means for changing the angle of the work-support;

Fig. 6, a view, chiefly in transverse section in the direction of the height of the machine, of the 30 drilling and screw-inserting mechanisms;

Fig. 11, a detail in perspective, illustrating the rack through which final pressure and locking effect is applied to the heel-clamping members.

45 Mounted side by side in the machine, at two operating stations, are a drilling mechanism A and a screw inserting mechanism B (Fig. 6), each of these having tools continuously rotated during the use of the machine and elevated alternately to perform their operations. The work may consist 50 of a shoe S upon a last L, and a heel H (Fig. 8) which is to be clamped temporarily to the heel-seat of the shoe. A passage l, extending through the cone of the last, is adapted to admit the drill of mechanism A and a screw b operated upon by mechanism B. The work is supported upon a 55

mechanism D, which presents it first to the drill and then to the inserting means, the movement from one to the other and the elevation and withdrawal of the tools being performed automatically under the power of the machine. The screw is supplied to the inserting mechanism manually by the operator.

The machine has a frame-column 10, which is inclined somewhat forwardly to give the operator more convenient access to the work-supporting mechanism D, which is above the upper extremity of the column (Fig. 1). In the column is situated the drilling mechanism A and the screw-inserting mechanism B, they being carried upon a casting 12 with which they may be removed from the machine as a unit. The work-support D consists of a lower carrier 14 (Fig. 8), upon which a lasted shoe may be placed with the cone of the last resting upon a finished surface or table at 16, and an upper carrier 18, upon which heel-engaging arms 20, 20 are mounted for bodily and pivotal movement to clamp and release a heel applied to the heel-seat of the shoe upon the lower carrier. The drilling and inserting mechanisms are raised and lowered to perform their operations through unvarying distances, and, since lasts have different vertical dimensions, and it is desired to have the tools operate always upon the work to the same extent, the entire work-support D has means by which it may be raised and lowered. This compensates for differences in the vertical position of the work. Mounted on ways 23 attached to the rear of the frame 10 is a slide 22 (Fig. 7) having at its opposite sides horizontal projections or brackets 24, 24, upon which are fulcrumed at 25, 25 generally vertical levers 26, 26 (Fig. 6). These levers oscillate between guides 27 attached to opposite sides of the frame. Between divided walls at the upper extremity of each lever is pivoted a block 28 (Figs. 2 and 4), having extending inwardly from it toward the opposite block a projection 30. Upon these projections, the lower carrier 14 of the work-support is pivotally mounted. The common axis of the two projections lies at the intersection of the table-surface 16 and the longitudinal axis of the passage 1 in a last positioned upon the table (Fig. 8). This allows the necessary angular movement of the table, with the minimum opening therein through which the mechanisms A and B are to operate. Formed with the member furnishing the ways 23 is a rack 34, with which meshes a segmental pinion 36 (Fig. 1) fast upon a transverse shaft 38 rotatable in the slide 22. Mounted to turn in the right-hand bracket 24 is a shaft 40, joined to the shaft 38 by worm-gearing 42. At the forward extremity of the shaft 40 is a crank 44. The operator, by turning the crank, may rotate the pinion 36, which, acting upon the stationary rack 34, will raise or lower the slide 22 and the work-support D, as desired. The opening 1 in lasts L, through which the drilling and screw-inserting operations are to occur, will vary as to the angles they make with the vertical axes of the last-cones, and to compensate for this the angle of the entire work-support D is correspondingly altered. Projecting from the blocks 28 are gear-segments 46, with which mesh segmental pinions 48 upon a shaft 50 journaled in the lower carrier 14. At the left-hand end of the shaft, worm-gearing 52 connects it to a shaft 54 extending in the carrier 14 from front to rear of the machine and having upon it a hand-wheel 56. When this is turned

by the operator, the movement is communicated through the shafts and pinions to the segments 46, and thus the angle of the work-support upon the levers 26 about the axes of the projections 30 5 altered and maintained.

The upper carrier 18 is pivoted about a shaft 60 (Figs. 2 and 8) journaled horizontally at the rear of the lower carrier 14, and has mounted upon it the spaced arms 20, 20 provided at their 10 forward extremities with curved pads 64, 64 arranged for engagement with the opposite sides and rear of a heel to be attached. The pads are secured to forward sections of the arms, which are swiveled upon projections 65 to turn about 15 generally horizontal axes. This permits self-adjustment of the engaging surfaces of the arms to heels of different contour. Each of the projections 65 is formed upon a slide 66 movable in vertical ways in the rear section or body-portion of the arm. Into each slide, a vertical screw 67 is threaded, the knurled head 69 of said screw turning in a slot in the carrier 18 to prevent longitudinal movement. By rotating either screw, the operator may position the corresponding pad 64 to most advantageously engage the particular form of heel being operated upon. Rotatable in spaced opposite side walls of the carrier 18 is a right-and-left screw 68. This screw is threaded through the body-portions of 20 the heel-engaging arms 20, which are prevented from turning about the screw by upward projections, upon each of which is a roll 70 running in a slot 72 in a bridge-piece 74 spanning the space between the side walls of the upper carrier. The arms 20 are arranged to be moved toward or from each other simultaneously by rotation of the screw 68, this being for the purpose of admitting, clamping and releasing a heel, and to be swung down and up to force the heel 25 against the heel-seat of a shoe and to relieve the pressure. The movement of the arms is accomplished by a rod 76 (Figs. 1 and 4), movable longitudinally through the right-hand side of the lower carrier and also rotatable in its mounting. It has upon its forward end a handle 78 by which it may be both reciprocated and rotated. In the longitudinal movement of the rod, spiral teeth 88 upon it mesh with a spiral-toothed segment 90 secured to the pivot-shaft 30 60 of the carrier 14. Also fast upon this shaft 60 is a segment 92, meshing with a pinion 94 upon the right-and-left screw 68. Therefore, the teeth 88 of the rod, acting as a rack, rotate the screw through the intermediate gearing to 55 carry the arms 20 oppositely either into or out of contact with the heel. During this longitudinal movement of the rod, it passes along a rack 96 (Figs. 2 and 11) mounted upon the side of the carrier 18 and splined into said rod. The teeth upon this rack are inclined, and, when the rod is rotated, its teeth 88, which circumferentially extend about only a portion of said rod, intermesh with the rack-teeth. The action of this rotation is to produce, through the camming effect resulting from the engagement of the opposed inclined teeth, a final longitudinal movement of the rod. This, by its action upon the right-and-left screw, urges the pads 64 of the arms forcibly against the heel and then locks said arms in their clamping position. The screw 68 has some capacity for axial play in its mounting, so the pressure of the arms upon the opposite sides of the heel may be equalized. Splined upon the rear extremity of the rod 76 is a segmental pinion 80 (Fig. 3), retained against lon-

itudinal movement in the upper carrier 13 and meshing with rack-teeth 81 formed upon the lower edge of a plate 82 guided in the lower carrier 14. In this bar are cam-slots 86, 86, which receive rolls 84 rotatable upon the upper carrier. When the rod 76 is rotated, the cam-plate is reciprocated, and the upper carrier is tilted vertically to either force the pads 64 down upon the heel or to raise them from it. Consequently, as the rotation of the rod applies final lateral clamping pressure to the heel, it settles it vertically firmly upon the heel-seat.

In placing the cone of a last L upon the surface 16 of the lower carrier 14 of the work-support D, the operator permits the forepart of the shoe to rest upon a member 100 (Figs. 1, 2 and 4), which is curved transversely of the machine and carried by a vertical spindle 102. This spindle is movable through, and may be clamped by a screw 101 in, a cross-piece 103 secured upon the forward ends of two spindles 104, 104, which are adjustable horizontally through the lower carrier. A screw 105 draws together a divided bearing for one of the spindles 104 to secure the cross-piece horizontally. By varying the position of the support 100 both horizontally and vertically, it may be adapted for such engagement with the forepart of a shoe that the end of the last-cone will rest properly upon the surface 16.

Initially, or at the beginning of an operating cycle, the levers 26, 26 are in such angular positions that an opening 108 (Fig. 6) in the carrier 14 is aligned with the drill mechanism A. When the drilling operation has been completed, the support-opening is transferred to a point above the tool of the inserting mechanism B by tilting the levers 26 about their fulcra. They are connected at their lower extremities by a link 110, having ways 112 inclined upwardly and forwardly and receiving a projecting portion 114 (Fig. 1) of a lever 116 fulcrumed at 115 upon the frame-column 10. To oscillate the lever, there is rotatable upon its lower end a roll 118, entering a cam-groove 120 in a cylindrical member 122 fast upon a shaft 124, journaled in the lower portion of the frame. The character of the connection between the link 110 and the lever 116 is such that the extent of movement of the opening 108 is unvaried, regardless of the vertical adjustment of the work-support by the crank 44. The cam-shaft 124 is rotated through a gear 126 from a pinion 127 on a main driving shaft 128 carrying tight and loose belt-pulleys 129. Connection between the shaft and gear is effected through clutch mechanism C, which, when twice tripped by a treadle T, causes the machine to perform a divided cycle.

The mechanism C (Fig. 1) comprises the clutch-proper c, which may be of the pin-type and which turns the pinion 127 when the treadle T is depressed by the operator to effect clutch-engagement. The treadle, normally held raised by a tension-spring 300 to the extent permitted by a stop-screw 301, has a plunger 302 urged up by an extension-spring 304. The upper extremity of the plunger engages the lower end of a substantially vertical arm 306 of a bell-crank-lever 308, fulcrumed near the bottom of the frame-column, to allow a horizontal arm 310 of the bell-crank to be raised by a tension-spring 311 to a position in which it will maintain the sections of the clutch separated, so the pinion 127 is at rest. An upwardly extending arm 312 of the bell-crank 308 contacts with the end of a substantially vertical arm 314 of a bell-crank-

lever 316, these arms being drawn yieldably together by the spring 311 connecting them. A horizontal arm 320 of the bell-crank 316 carries a roll 322 projecting into a cam-groove 324 formed in one face of the gear 126. When the operator actuates the treadle, its plunger 302 forces aside the lever-arm 310, lowering the arm 310 to free the clutch c, so this is engaged and rotation of the pinion 127 is initiated to drive the cam-shaft 124. At this time, the spring 311 yields. The plunger 302 passes the end of the arm 306 and releases it, so the arm 310 tends to rise under the influence of the spring 311 into position for disengaging the clutch c. But as the gear 126 rotates, its cam-groove 324 causes the bell-crank 316 to force its arm 314 against the arm 312 of the bell-crank 308. This retains the lever-arm 310 in its inactive relation, so the clutch continues to drive the pinion 127 through the desired number of turns to give partial rotation of the gear 126 and produce the first period of the divided cycle. At this time, the cam-groove so positions the bell-crank 316 that the arm 310 is raised to open the clutch, and rotation of the cam-shaft 124 stops. Then, upon the succeeding depression of the treadle by the operator, the clutch is engaged as before, the cam-groove in the now rotating gear permitting the bell-crank 316 to assume its initial position and the lever-arm 310 to rise and disengage the clutch as the final turn of the pinion 127 is completed. Thus, the second period of the cycle comes to an end. Each time the operator releases the treadle, an inclined end-face 326 upon the plunger 302 strikes a complementally inclined face 328 upon the lever-arm 306. This cams down the plunger, so it may be drawn past the lever-arm by the spring 300, ready for the succeeding operation. The purpose of the divided cycle will be stated in connection with the outline of operation of the machine.

Considering the drilling mechanism A, there is arranged to both rotate in and reciprocate vertically through the left-hand side of the casting 12, a spindle 140 (Fig. 6). At the upper extremity of the spindle is a bore to receive the tubular shank 141 of a chuck 142. In this chuck, a drill 144 may be secured by a set-screw 146, it being movable through an opening 147 in the closed top of the column 10. The flanged lower portion of the chuck is rotatable about the enlarged end 145 of the spindle, there being upon opposed surfaces of the two members opposite projections 148 and 150. Interposed between the lower extremity of the chuck and the bottom of the bore in the spindle is a compression-spring 152, resting upon an antifriction-ball 154. The spring elevates the chuck to an extent permitted by contact of a separable ring 155, at the bottom of said chuck, with the spindle-enlargement 145. This normally separates the projections 148 and 150, so the drill is at rest. When, however, the point of the drill strikes the work, compression of the spring allows the spindle-projection 150 to rise into the plane of the chuck-projection 148, and the rotation of the drill begins. The drill bottoms upon a screw 156 threaded into the drill-receiving passage of the chuck. The drill is provided with a slot arranged to receive a bit or projection 159 at the upper extremity of the screw. By this engagement, upon rotation of the drill after the set-screw 146 is loosened, the height of the drill in the chuck may be varied. Constant rotation is imparted to the spindle 140 by spiral gearing

160 joining it to a shaft 162, journaled horizontally in the frame-column and rotated by belt-gearing 164 from a parallel shaft 163, journaled at the bottom of the column and geared to the driving shaft 128 at 165.

To reciprocate the spindle 140, so the drill may be elevated to perform its operation upon the work and retracted, a gear-segment 166 furnishes an arm of a bell-crank-lever 168 fulcrumed at 169 upon the frame-column and oscillated by the entrance of a roll 170 upon it into a cam-groove 172 in one face of the cylinder 122. The segment engages a pinion 174 fast upon a shaft 176, journaled horizontally in the frame adjacent to the spindle 140. Attached at one extremity to the shaft 176 is a torsion-spring 178 (Fig. 6), which, at its opposite end, is received in an opening in a gear 180 rotatable about the shaft 176. This gear has teeth so curved as to properly engage circular teeth 182 formed about the lower end of the spindle 140. When movement of the cam-groove 172 causes the bell-crank-lever 168 to turn the pinion 174, force is transmitted through the torsion-spring to the gear 180 to raise the drill-spindle. As a result of this yieldable actuation, if the drill in its elevation contacts with some object in the work, such as a shank-piece, which might cause breakage, injury to the elements is prevented.

As to the mechanism B for inserting a screw *b*, this includes a spindle 190 guided for vertical movement through an upwardly extending tubular portion 191 of the casting 12, and having located within an axial bore a concentric inner spindle 192. Threaded upon the upper extremity of the latter spindle is a chuck 194, movable through an opening 195 in the top of the column and provided with a slot 196 to receive the circular head of the standard temporary-attaching screw *b*. The chuck is counterbored at 200, into which counterbore fits the washers *w* which the screw carries. By the engagement of the screw-head with the slot and the washers with the counterbore, the screw is compelled to turn with the chuck and the shank of said screw is held in substantial alinement with the inner spindle 192. Surrounding this spindle, and somewhat spaced from the chuck, is a connecting and driving sleeve 204, upon which is a tooth 206 for engagement with a tooth 208 upon the upper extremity of the outer spindle 190. These teeth or projections are held normally separated by a spring 210 interposed between the lower end of the inner spindle and the bottom of the bore in the outer spindle. Extending horizontally from the spindle 192 is a projection 212 lying within a cam-slot 214 in the sleeve 204. Connecting the upper end of the driving sleeve to the chuck 194 is a torsion-spring 216 stronger than the spring 210. Relative vertical movement of the two spindles is limited by a projection 218 from the outer into a circumferential slot 220 in the inner. This projection is extended circumferentially of the spindles for the sake of strength. It will be seen that when the chuck has received a screw *b* and the outer spindle 190 is elevated, the inner spindle 192 will be correspondingly raised until the screw, co-operating with the hole which has been drilled in the work, encounters sufficient resistance to compress the spring 210. When this occurs, since the strength of the spring 216 prevents its compression, the tooth 208 will rise into the plane of the tooth 206, and when they are engaged the rotation of the spindle 190 will drive the sleeve 204. This, in turn,

will communicate the rotation through the torsion-spring 216 to the chuck 194, and thus turn the screw *b*, causing its insertion in the drilled hole. This continues until the resistance to rotation of the screw, because of the fact that its insertion is nearly or quite completed, causes the flexing of the spring 216 and the relative movement of the sleeve 204 and the projection 212 longitudinally of the spindle-axis. When the spring is thus flexed, the washers *w* upon the screw will generally have come into contact with the end of the cone of the last *L* and there will be exerted the maximum force, acting against this resistance, to set the screw and to draw the heel *H* firmly against the heel-seat of the shoe *S*. Since the inner spindle cannot descend, because at this time the projection 218 is at the top of the slot 220, the effect of the relative movement between the slot 214 and the projection 212 is to cam up the sleeve 204, compressing the convolutions of the torsion-spring 216. This separates the projections 206, 208 and stops the rotation of the screw. With the sleeve thus released, it will assume its initial circumferential relation to the inner spindle 192, and if the full elevation of the spindle 190 has not been completed, the projections 206 and 208 will again be engaged. An added rotating force will therefore be applied to the screw *b* to an extent permitted by the resistance of the torsion-spring 216.

30 The manner of elevation of the spindle 190 of the inserting mechanism resembles that of the spindle 140 of the drilling mechanism. At the opposite face of the cam-cylinder 122 from that containing the groove 172 which oscillates the bell-crank-lever 168, is another cam-groove 230 (Fig. 1) for producing the oscillation of a bell-crank-lever 232, a roll 233 upon which enters the groove. A gear-segment 234 upon this lever engages a pinion 236 upon a shaft 238, rotatable in the frame in alinement with the shaft 176. A torsion-spring 240 (Fig. 6) joins the shaft to a gear 242, which meshes with the circular teeth 244 upon the spindle 190. Consequently, the advance of the tool is effected yieldably, so damage will not be caused by excessive resistance to movement, as by tearing out the thread which the screw *b* forms in the work. The spindle 190 is rotated, as in the companion mechanism, from the constantly rotating shaft 162 through spiral gearing 246.

55 To hold the screw *b* in the proper position to enter the opening *l* in the last *L* and be turned into the work, there is associated with the inserting mechanism B a pair of screw-engaging fingers 250, 259. These are pivoted at 252 at opposite sides of the passage in the guide-portion 191 of casting 12, through which the screw-inserting spindles operate, and are bent in at their upper extremities 254 above the end of the guide-portion, being there formed with depressions to admit the end of the screw. At the inner side of each finger-end 254 is a wall 256, inclined upwardly and inwardly, to direct the screws into the opening furnished by the depressions. Each finger is fast upon its pivot-portion 252, and there are also secured to these pivots respective arms 258 and 260 (Fig. 10). The arm 258 has a projection 262 entering a slot lying longitudinally of the arm 260. This latter arm is extended outwardly at 264 and has attached to it at 266 a vertical rod 268 (Fig. 1), forced normally down by a spring 270. At the lower end of the rod a roll 272 is rotatable, this resting against a cam 70 274 upon the shaft 238. This cam is of such con-

tour, that during a period of rest the fingers are separated against the closing force of the spring, so the operator may insert the head of the screw *b* into the slot of the chuck *194*. When the cam rotates, it allows the fingers to be closed by the spring to align the screw for its insertion, they being thereafter separated, so the chuck may rise and turn said screw into the work. The screw is held in approximately the true axial relation at the time of its introduction into the chuck, by its washers *w* fitting closely within the counterbore *203*.

At the beginning of an operating cycle, the drill *144* of the mechanism *A* is raised through the opening *147* in the top of the column *10* and through the opening *108* of the work-carrier *14*, with its point above the surface *16* of the latter, its spindle *140* being in rotation. The drill, however, is at rest, because the spindle-projection *150* and the chuck-projection *148* are separated vertically. It therefore cannot bore into the last-cone, through accidental contact with it. The chuck *194* of the inserting mechanism *B* is lowered, contains a screw *b*, and its spindle *190* is rotating. The screw is aligned with the spindle, and therefore with the opening *195* at the top of the column, by the fingers *250*, closed by the cam *274*. The operator, taking a shoe *S* and a heel *H*, places the crown of the cone of the last *L* in the former upon the surface *16* of the support *D*, with the last-passage receiving the elevated and stationary drill-point to correctly locate the work. The forepart of the shoe is supported by the rest *100*. The heel, with adhesive applied to its cup, is placed upon the heel-seat of the shoe, and the rod *76* pulled forward by the handle *78* to turn the right-and-left screw *68*, bringing the pads *64* of the previously open arms *20* into preliminary contact with the opposite sides of the heel. As this engagement with the work is effected, the rod is rotated clockwise by the handle to produce, through the engagement of the teeth *88* upon the rod and on the fixed rack *96*, a final clamping of the pads against the heel and to lock the arms against retraction. Simultaneously, the rotation of the rod shifts the cam-plate *82*, forcing the cup of the heel against the heel-seat by the tilting of the carrier *13*. The treadle *T* of the machine is now depressed, causing the mechanism *C* through the clutch *c* to rotate the cam-shaft *124* for the first period of the divided cycle. The cam-groove *172* at the left end of the cylinder *122* causes the elevation of the constantly rotating drill-spindle *140*, so the drill passes through the opening in the last and, upon engagement of its point with the insole of the shoe, is driven to produce in the heel-seat and heel a hole of the desired depth (Fig. 4). It is then retracted to a point below the carrier *14* of the support (Fig. 6). For the particular last in use, the depth of drilling will have been determined by the height of the work-support *D*, through elevation or depression of the slide *22*, with the carrier-levers *26*, as a result of rotation of the crank *44* (Fig. 1). The angle of the last-opening, to agree with that of the drill, will also have been determined by tilting the work-support about the projections *30*, through rotation of the hand-wheel *56* (Fig. 2). When the cam-groove *172* has completed this operation of the drilling mechanism *A*, the peripheral groove *120* in the cylinder *122* shifts the work-support from its position at the left of the frame to the right, so the table-opening *103* and the last-passage *l* of the clamped work are now

aligned with the column-opening *195* above the inserting mechanism *B*. The cam-groove *230* at the right end of the cylinder produces the elevation of the rotating spindle *190* with the screw *b* which it carries in the non-rotating chuck *194*. The fingers *250*, *250* remain closed, as the screw first rises, it separating them against the force of the spring *270* and being maintained in alignment with the last-passage. But when the point of the screw is within the passage, so it cannot be displaced laterally, the fingers are opened by the cam *274* to permit the movement of the chuck *194* between them. When the screw-threads engage the wall of the drilled opening in the work, its rotation begins through the engagement of the tooth *208* upon the spindle *190* with the tooth *206* of the driving sleeve *204*, and it is turned home. At the termination of the first period of the cycle, the machine stops with drill *144* lowered and the chuck *194* raised, both being at rest and the fingers *250* now being open. The operator reversely rotates and thrusts back the rod *76* to unlock and retract the arms *20*. He then removes from the support the released shoe with its temporarily attached heel, applies another screw to the chuck *194* and again treads. The clutch *c* is reengaged to complete the cycle. At this time, the fingers close against the screw to align it; the chuck with the screw is lowered to its normal position; and the work-support travels to the left, into co-operation with the drilling mechanism *A*. This is as represented in Fig. 6. Finally, the drill is elevated, so that it will be above the surface *16* of the work-support ready to position the succeeding work. This completes the full cycle, and the mechanism *C* opens the clutch *c* to stop the cam-shaft.

Having described my invention, what I claim as new and desire to secure by Letters Patent of the United States is:

1. In a fastening-inserting machine, means for forming a hole in a work-piece and for inserting a fastening therein, said means being located at different operating stations, a movable work-support, and means acting under the power of the machine for moving the support from the hole-forming to the fastening-inserting station and reversing the travel of the support to return it to the hole-forming station.

2. In a screw-inserting machine, rotatable operating means for forming a hole in a work-piece and for inserting a screw therein, a movable work-support, and means acting under the power of the machine for reciprocating the support to present the work to the operating means for the successive formation of the hole and the turning of the screw into said hole and for determining the time of operation of the operating means.

3. In a machine for attaching heels to shoes upon lasts, a support for a lasted shoe, means operating through the last for forming a hole in the heel-seat of the supported shoe and in an applied heel and for inserting a fastening in the hole thus formed, and means acting under the power of the machine for moving the support and operating means relatively to present the lasted shoe successively for the forming and inserting operations.

4. In a machine for attaching heels to shoes upon lasts, a support for a lasted shoe, means operating through the last for forming a hole in the heel-seat of the supported shoe and in an applied heel and for inserting a fastening in the hole thus formed, and means acting under the

power of the machine for moving the support and operating means relatively to present the lasted shoe successively for the forming and inserting operations and for moving the operating means to produce through the last the forming operation and thereafter the inserting operation.

5. In a fastening-inserting machine, a reciprocatory drill, a reciprocatory fastening-inserting device, a work-support initially positioned and retained against movement to receive the action of the drill, and means for moving the support to a position to receive the action of the inserting device, holding it against movement during such action and then returning it to its initial position at the drill.

6. In a fastening-inserting machine, a reciprocatory drill, a reciprocatory fastening-inserting device, a work-support initially positioned to receive the action of the drill, means for moving the support to a position to receive the action of the inserting device and then returning it to its initial position at the drill, and means acting while the support is at the inserting device for temporarily retaining said device in its inserting position to receive the succeeding fastening.

7. In a fastening-inserting machine, a reciprocatory drill, a reciprocatory fastening-inserting device, a work-support initially positioned to receive the action of the drill, and means for moving the support to a position to receive the action of the inserting device, for returning it to its initial position at the drill and for retracting the device for the return of the support.

8. In a machine for operating through passageways in lasts within shoes, a work-support having a surface upon which the cone of a last may rest, a tool movable through the passage to operate upon the supported work, and means for advancing the tool through a portion only of its operating movement above the support-surface, for stopping the tool to permit the application thereto of the last-passage and for completing its operating advance.

9. In a fastening-inserting machine, a reciprocatory drill, a reciprocatory fastening-inserting device, a work-support initially positioned to receive the action of the drill, means for moving the support to a position to receive the action of the inserting device and then returning it to its initial position at the drill, and means for advancing the drill through a portion only of its operating movement while the support is in its initial position, for stopping said drill to serve as a gage for the work and for completing its operating advance.

10. In a fastening-inserting machine, a reciprocatory drill, a reciprocatory fastening-inserting device, a work-support initially positioned to receive the action of the drill, means for moving the support to a position to receive the action of the inserting device and then returning it to its initial position at the drill and for retracting the device for the return of the support, and means for advancing the drill through a portion only of its operating movement while the support is in its initial position, for stopping said drill to serve as a gage for the work and for completing its operating advance.

11. In a fastening-inserting machine, a reciprocatory drill, a reciprocatory fastening-inserting device, a work-support initially positioned to receive the action of the drill, and a cam constructed and arranged to move the support to a position to receive the action of the inserting device

70 75 and to then return it to its initial position at the drill.

12. In a fastening-inserting machine, a reciprocatory drill, a reciprocatory fastening-inserting device, a work-support initially positioned to receive the action of the drill, a cam constructed and arranged to move the support to a position to receive the action of the inserting device and to then return it to its initial position at the drill, a cam for reciprocating the drill, and a cam for reciprocating the inserting device.

13. In a heel-attaching machine, a frame-column, a work-support mounted thereon, a secondary frame separably secured against movement 15 within the column, and drill mechanism and fastening-inserting mechanism movable upon the secondary frame through the top of the column in co-operation with the work-support and being removable together from the column upon the secondary frame.

14. In a heel-attaching machine, a main frame, a work-support mounted thereon, a secondary frame separably secured to the main frame, drill mechanism and fastening-inserting mechanism 20 movable upon the secondary frame in co-operation with the work-support and being removable together from the main frame upon the secondary frame, and gearing having intermeshing portions carried respectively upon the main frame and upon the secondary frame for actuating the drill mechanism and the fastening-inserting mechanism.

15. In a fastening-inserting machine, a support arranged to receive contact of the cone of a last within a shoe, a tool for operating upon the work through the support and through a passage in the last, an actuating member by which the tool is carried, means for moving the actuating member normally through an unvarying distance to produce the action of the tool upon the work, and means arranged to change the initial relation between the support and actuating member and thereby compensate for different heights of last cones.

16. In a machine for inserting heel-attaching screws through passages in lasts within shoes, said screws entering heels applied to the heel-seats of the shoes and bearing upon the cones of the lasts, a support for the lasted shoes, a screw-driver co-operating with the support for engagement with the screws, a rotatable spindle for the screw-driver, means for reciprocating the spindle normally through an unvarying distance in its action upon the screws, and means arranged to move the support in the direction of reciprocation of the spindle as the cones of the lasts differ in height.

17. In a heel-attaching machine, a drill, a screw-driver, means for rotating and reciprocating the drill and screw-driver, a support upon which a shoe and heel may be subjected to the action of the drill and screw-driver, means for moving the support to present the work successively to said drill and screw-driver, and means arranged to move the support toward and from the drill and screw-driver.

18. In a heel-attaching machine, a frame, a reciprocatory tool movable upon the frame for operating upon a heel, a slide guided upon the frame, a support for a shoe and heel carried by the slide and with which the tool co-operates, means including a rotatable gear through which the slide is movable, and means arranged for actuation by the operator and extending to the front of the frame for rotating the gear.

19. In a heel-attaching machine, a frame, a tool movable upon the frame for operating upon a heel, a slide guided upon the frame, a work-support carried by the slide and with which the tool co-operates, an adjusting device movable upon the slide by the operator, and gearing connecting the device and frame. 5
20. In a heel-attaching machine, a frame, a tool movable upon the frame for operating upon a heel, a slide guided upon the frame, a work-support carried by the slide and with which the tool co-operates, a shaft journaled transversely of the slide, gearing connecting the shaft and frame, an operator-controlled shaft journaled upon the slide and extending toward the front 10 of the machine, and gearing connecting the shafts. 15
21. In a heel-attaching machine for operating through passages in lasts within shoes, the passages in different lasts differing in their angular relation to the axes of the last-cones, a support against which the crown of a last may rest, a tool operating through the support and last-passages, and means arranged to change the angle between the tool and the passage in the supported last to compensate for variations in the last-passages. 20
22. In a heel-attaching machine for operating through passages in lasts within shoes, the passages in different lasts differing in their angular relation to the axes of the last-cones, a support upon which the cone of a last may rest with the shoe bottom-up, a tool operating upwardly through the support and last-passages, and means arranged to change the angle of the support to compensate for variations in the last-passages. 25
23. In a heel-attaching machine for operating through passages in lasts within shoes, the passages in different lasts differing in their angular relation to the axes of the last-cones, a support upon which the cone of a last may rest with the shoe bottom-up, a tool operating upwardly through the support and last-passages, and means arranged to change the angle of the support to compensate for variations in the last-passages, such angular movement occurring about an axis approximately intersecting the longitudinal axis of the tool. 30
24. In a heel-attaching machine, a movable tool for operating upon a heel, a work-support with which the tool co-operates, a movable member upon which the support is pivotally mounted, a shaft journaled upon the support for rotation by the operator, and gearing connecting the mounting member and the shaft. 35
25. In a heel-attaching machine, a movable tool for operating upon a heel, a work-support with which the tool co-operates, a movable member upon which the support is pivotally mounted, a shaft journaled transversely of the support, gearing connecting the mounting member to the shaft, a shaft journaled upon the support and extending toward the front of the machine for rotation by the operator, and gearing connecting the shafts. 40
26. In a heel-attaching machine, a plurality of movable tools for operating upon a heel, a work-support with which the tools co-operate, a member upon which the support is pivotally mounted and which is movable to present the supported work to either of the tools, and means joining the mounting member to the support and arranged to vary the angle of said support. 45
27. In a heel-attaching machine, a plurality of movable tools for operating upon a heel, a work-support with which the tools co-operate, spaced levers, mounting members pivoted upon the levers and upon which the support is pivoted, and gearing connecting one of the mounting members to the support and arranged for actuation by the operator. 50
28. In a heel-attaching machine, a drill and a screw-driver mounted side by side, means for rotating and reciprocating the drill and screw-driver, a support for a shoe and heel, means for moving the support to subject the shoe and heel alternately to the action of the drill and screw-driver, means arranged to move the support toward and from the drill and screw-driver, and means arranged to vary the angle of the support. 55
29. In a heel-attaching machine, a shoe-support, opposite heel-clamps co-operating with the support, and an actuating member having a compound movement, one of the components of said movement causing the clamps to engage a heel upon a supported shoe and another of the components acting to force the heel against the heel-seat of said shoe. 60
30. In a heel-attaching machine, a shoe-support, opposite heel-clamps co-operating with the support, and an actuating member having a compound movement, one of the components of said movement causing the clamps to engage a heel upon a supported shoe and another of the components acting to produce a final clamping effect. 65
31. In a heel-attaching machine, a shoe-support, opposite heel-clamps co-operating with the support, and an actuating member having a compound movement, one of the components of said movement causing the clamps to engage a heel upon a supported shoe and another of the components acting to produce a final clamping effect and to force the heel against the heel-seat of said shoe. 70
32. In a heel-attaching machine, a shoe-support, opposite heel-clamps co-operating with the support, and an actuating member having a movement of reciprocation and rotation, the reciprocatory movement causing the clamps to engage a heel upon a supported shoe and the rotary movement acting to force the heel against the heel-seat. 75
33. In a heel-attaching machine, a shoe-support, a right-and-left screw mounted adjacent to the support, opposite heel-clamps threaded upon the screw to receive upon its rotation a bodily movement, and means arranged to rotate the screw. 80
34. In a heel-attaching machine, a shoe-support, a right-and-left screw mounted adjacent to the support, opposite heel-clamps threaded upon the screw to receive upon its rotation a bodily movement, means for preventing the clamps from tilting upon the screw, and means arranged to rotate the screw. 85
35. In a heel-attaching machine, a shoe-support, a right-and-left screw mounted adjacent to the support, opposite heel-clamps threaded upon the screw, a reciprocatory rod provided with teeth, and gearing connecting the toothed rod to the screw. 90
36. In a heel-attaching machine, a shoe-support, a right-and-left screw mounted adjacent to the support, opposite heel-clamps threaded upon the screw, a rotary and reciprocatory rod provided with teeth, gearing connecting the toothed rod to the screw, and a stationary toothed member into engagement with which the teeth of the rod may be turned. 95

37. In a heel-attaching machine, a shoe-support, a carrier pivoted adjacent to the support, opposite clamps mounted for bodily movement along the carrier to engage a heel, and means arranged to rock the carrier about its pivot to force the engaged heel against the heel-seat of a supported shoe.
38. In a heel-attaching machine, a shoe-support, a carrier pivoted adjacent to the support, opposite clamps movable upon the carrier to engage a heel, a cam movable to rock the carrier about its pivot, and means arranged to actuate the cam.
39. In a heel-attaching machine, a shoe-support, a carrier pivoted adjacent to the support, opposite clamps movable upon the carrier to engage a heel, a reciprocatory cam engaging the carrier, a member movable upon the support by the operator, and gearing connecting said member with the cam.
40. In a heel-attaching machine, a shoe-support, a carrier movable adjacent the support, a right-and-left screw rotatable upon the carrier, opposite heel-clamps threaded upon the screw, means arranged to turn the screw, and interengaging means upon the carrier and clamps whereby tilting of the clamps upon the screw is prevented.
41. In a heel-attaching machine, a shoe-support, a carrier pivoted upon the support, a right-and-left screw rotatable upon the carrier, opposite heel-clamps threaded upon the screw, a rod movable upon the support, and means whereby movement of the rod will rotate the screw and tilt the carrier upon the support.
42. In a heel-attaching machine, a shoe-support, a carrier pivoted upon the support, a right-and-left screw rotatable upon the carrier, opposite heel-clamps threaded upon the screw, a cam movable upon the support and acting upon the carrier, a rotary and reciprocatory rod movable upon the support, gearing connecting the rod and screw, and gearing connecting the rod and cam.
43. In a heel-attaching machine, a shoe-support, a carrier pivoted upon the support, a right-and-left screw rotatable upon the carrier, opposite heel-clamps threaded upon the screw, a cam movable upon the support and acting upon the carrier, a rotary and reciprocatory rod movable upon the support, gearing connecting the rod and screw, gearing connecting the rod and cam, the gearing between the rod and screw having spiral teeth, and a rack provided with spiral teeth fixed in the support and into engagement with which the spiral teeth of the rod-gear may move.
44. In a heel-attaching machine, a shoe-support, a carrier movable adjacent the support, opposite heel-clamps having body-portions movable toward and from each other upon the carrier, slides movable upon the body-portions, and heel-engaging portions swiveled upon the slides.
45. In a heel-attaching machine, a shoe-support, a carrier movable adjacent the support, a right-and-left screw rotatable upon the carrier, spaced arms threaded upon the screw, slides movable upon the arms, heel-engaging pads swiveled upon the slides, and means arranged to rotate the screw.
46. In a heel-attaching machine, a shoe-support, a carrier movable adjacent the support, a right-and-left screw rotatable upon the carrier, spaced arms threaded upon the screw, slides movable upon the arms, heel-engaging pads
- swiveled upon the slides, and means arranged to rotate the screw and to rock the carrier upon the shaft.
47. In a heel-attaching machine, a plurality of tools for operating upon a heel, spaced levers, a work-support pivotally mounted upon the levers and with which the tools co-operate, and means for oscillating the levers to present the work-support to different tools.
48. In a heel-attaching machine, a plurality of tools for operating upon a heel, spaced levers, a work-support pivotally mounted upon the levers and with which the tools co-operate, a link connecting the levers, a lever acting upon the link, and a cam for oscillating the last-mentioned lever.
49. In a heel-attaching machine, a plurality of tools for operating upon a heel, a slide, means arranged to differently position the slide, spaced levers fulcrumed upon the slide, a work-support pivotally mounted upon levers and with which the tools co-operate, and means for oscillating the levers.
50. In a fastening-inserting machine, a work-support movable between hole-forming and fastening-inserting positions and reversely, means movable at the respective positions to form a hole in a supported work-piece and to insert a fastening therein, said means performing the operations in a divided cycle with an intermediate period of rest occurring while the work-support is at the hole-forming position, and a member arranged for actuation by the operator to initiate the successive portions of the cycle.
51. In a fastening-inserting machine, a work-support, means reciprocable to form a hole in a supported work-piece and to insert a fastening therein, said means performing the operations in a divided cycle with an intermediate period of rest occurring after the insertion of the fastening and before the retraction of the inserting means, and a member arranged for actuation by the operator to initiate the successive portions of the cycle.
52. In a fastening-inserting machine, a work-support, means reciprocable to form a hole in a supported work-piece and to insert a fastening therein, said means performing the operations in a divided cycle with an intermediate period of rest occurring after the insertion of the fastening and after a partial advance of the hole-forming means, and a member arranged for actuation by the operator to initiate the successive portions of the cycle.
53. In a fastening-inserting machine, a work-support, means reciprocable to form a hole in a supported work-piece and to insert a fastening therein, said means performing the operations in a divided cycle with an intermediate period of rest occurring after the insertion of the fastening and before the retraction of the inserting means and after a partial advance of the hole-forming means, and a member arranged for actuation by the operator to initiate the successive portions of the cycle.
54. In a heel-attaching mechanism, a support for a shoe with an applied heel, movable drill mechanism and fastening-inserting mechanism co-operating with the support, clutch mechanism through which the drill and fastening-inserting mechanisms are moved, a controlling member movable by the operator to cause the engagement of the clutch mechanism, said member thereupon releasing the clutch mechanism, and means movable under the power of the machine for

temporarily maintaining the engagement of the clutch mechanism and thereafter disengaging said mechanism to terminate one portion of an operating cycle in preparation for a second movement of the controlling member by the operator to complete the operating cycle.

55. In a heel-attaching mechanism, a support for a shoe with an applied heel, movable drill mechanism and fastening-inserting mechanism co-operating with the support, clutch mechanism through which the drill and fastening-inserting mechanisms are moved, a member movable by the operator to cause the engagement of the clutch mechanism, said member thereupon releasing the clutch mechanism, and means movable under the power of the machine for temporarily maintaining the engagement of the clutch mechanism and thereafter disengaging said mechanism to terminate one portion of an operating cycle, the power-operated means upon the succeeding movement of the operator-controlled member permitting a second disengagement of the clutch mechanism to terminate the second portion of the operating cycle.

56. In a heel-attaching machine, a support for a lasted shoe, the last being provided with a passage through its cone, a drill adapted to bore a hole through the heel-seat of the shoe into an applied heel, said drill being arranged to enter the last-passage and by its engagement with the last to position the work upon the support, and means for clamping the positioned work upon the support.

57. In a heel-attaching machine, a support for a lasted shoe, the last being provided with a passage through its cone, a drill arranged to enter the last-passage to position the work upon the support, means for clamping the positioned work upon the support, means for reciprocating the drill through the last-passage, and means for rotating the drill only after its contact with the insole of a shoe.

58. In a heel-attaching machine, a support for a lasted shoe, the last being provided with a passage through its cone, a drill arranged to enter the last-passage to position the work upon the support at an operating station, means for clamping the positioned work upon the support, means for rotating the drill, and means arranged to move the support and present the clamped work at a second operating station.

59. In a heel-attaching machine, a support for the cone of a last within a shoe, there being a passage through the last-cone, a drill arranged with its point extending beyond the last-engaging surface of the support, means for moving the support and drill relatively to cause contact through the last-passage between the drill point and the insole of the shoe, and means effective to rotate the drill only after said contact.

60. In a heel-attaching machine, a table provided with an opening, said table being adapted to support the cone of a last within a shoe, there being a passage through the last-cone for registration with the table-opening, a drill having its point initially extending through the table-opening to enter the last-passage, and means for rotating the drill only after contact of its point with the shoe.

61. In a heel-attaching machine, a table provided with an opening, said table being adapted to support the cone of a last within a shoe, there being a passage through the last-cone for registration with the table-opening, a drill having its point initially extending through the

table-opening to enter the last-passage, a rotatable driving spindle for the drill, means for reciprocating the spindle, and means effective to rotate the drill upon reciprocation of the spindle.

62. In a heel-attaching machine, a table provided with an opening, said table being adapted to support the cone of a last within a shoe, there being a passage through the last-cone for registration with the table-opening, a drill having its point initially extending through the table-opening to enter the last-passage, a chuck in which the drill is held, a rotatable driving spindle, means upon the spindle and chuck arranged for driving engagement, and a spring maintaining the engaging means normally separated.

63. In a heel-attaching machine, a shoe-support, a rotatable chuck provided with a passage, a screw threaded into the passage, a drill entering the passage and cooperating with the shoe-support, the screw and drill having an interengaging depression and projection, and means for securing the drill in the chuck.

64. In a heel-attaching machine, a shoe-support, a tool-spindle co-operating with the support, means for rotating the spindle, a movable actuating member, gearing connecting the actuating member and spindle to reciprocate said spindle, and means for permitting an element of the gearing to yield during its action upon the spindle.

65. In a heel-attaching machine, a shoe-support, a tool-spindle co-operating with the support, means for rotating the spindle, a lever, means for oscillating the lever, gearing connecting the lever and spindle to reciprocate said spindle, and means permitting an element of the gearing to yield in its reciprocating action.

66. In a heel-attaching machine, a shoe-support, a tool-spindle co-operating with the support and provided with rack-teeth, means for rotating the spindle, a movable actuating member, a shaft, gearing connecting the actuating member and shaft, a gear arranged to turn about the shaft and meshing with the rack-teeth, and a spring joining the shaft and gear.

67. In a heel-attaching machine, a shoe-support, and screw-inserting mechanism co-operating therewith and comprising a driving spindle, a screw-driver carried by the spindle, said screw-driver and spindle being arranged for relative longitudinal movement and a connecting member movable longitudinally of the spindle and screw-driver and yieldably joined to said screw-driver, the spindle and connecting member being provided with engaging portions.

68. In a heel-attaching machine, a shoe-support, and screw-inserting mechanism co-operating therewith and comprising a driving spindle, a screw-driver carried by the spindle, said screw-driver and spindle being arranged for relative longitudinal movement, a connecting member movable longitudinally of the spindle and screw-driver and yieldably joined to said screw-driver, the spindle and connecting member being provided with engaging portions and means for limiting the relative longitudinal movement of the spindle and screw-driver.

69. In a heel-attaching machine, a shoe-support, and screw-inserting mechanism co-operating therewith and comprising a driving spindle, a screw-driver carried by the spindle, said screw-driver and spindle being arranged for relative longitudinal movement, a connecting member movable longitudinally of the spindle and screw-driver and yieldably joined to said screw-driver,

the spindle and connecting member being provided with engaging projections and means carried by the connecting member and screw-driver for separating the projections upon yield of the connecting member.

70. In a heel-attaching machine, screw-inserting mechanism comprising a driving spindle, a screw-driver provided with a spindle, a spring interposed between the spindles to permit their relative longitudinal yield, a sleeve surrounding the screw-driver-spindle, said sleeve and driver-spindle having engaging portions normally separated by the spring, a spring connecting the sleeve and screw-driver, and means arranged to produce relative longitudinal movement between the sleeve and the screw-driver-spindle.

71. In a heel-attaching machine, screw-inserting mechanism comprising a driving spindle, a screw-driver provided with a spindle, one of the spindles being provided with a projection extending into a depression in the other, a spring interposed between the spindles to permit their relative longitudinal yield, a sleeve surrounding the screw-driver-spindle, said sleeve and driver-spindle having engaging portions normally separated by the spring, a spring connecting the sleeve and screw-driver, and means arranged to produce relative longitudinal movement between the sleeve and the screw-driver-spindle.

72. In a heel-attaching machine, screw-inserting mechanism comprising a driving spindle, a screw-driver provided with a spindle, the two spindles being concentric, a compression-spring interposed between the spindles to permit their relative longitudinal yield, a sleeve surrounding the screw-driver-spindle, said sleeve and driver-spindle having engaging portions normally separated by the spring, a torsion-spring connecting the sleeve and screw-driver, and means arranged to produce relative longitudinal movement between the sleeve and the screw-driver-spindle.

73. In a heel-attaching machine, screw-inserting mechanism comprising a driving spindle, a screw-driver provided with a spindle, the two spindles being concentric, a spring interposed between the spindles to permit their relative longitudinal yield, a sleeve surrounding the screw-driver-spindle, said sleeve and driver-spindle having engaging portions normally separated by the spring, and a spring connecting the sleeve and screw-driver, the sleeve and screw-driver-spindle being provided with a cam-slot and a projection lying in said slot.

74. In a heel-attaching machine, a shoe-support, drill mechanism having a spindle co-operating with the support, screw-driver mechanism having a spindle co-operating with the support, means for moving the support to present a shoe upon it to either the drill mechanism or the screw-driver mechanism, means for rotating each spindle, a movable actuating member for each spindle, and gearing connecting each actuating member to its spindle to reciprocate said spindle when the work is presented to it.

75. In a heel-attaching machine, a shoe-support, drill mechanism having a spindle co-operating with the support, screw-driver mechanism having a spindle co-operating with the support, means for moving the support to present a shoe upon it to either the drill mechanism or the screw-driver mechanism, means for rotating each spindle, a movable actuating member for each spindle, gearing connecting each actuating member to its spindle to reciprocate said spindle when the work is presented to it, and means for per-

mitting an element of the gearing for each actuating member to yield during its action upon the spindle.

76. In a heel-attaching machine, a shoe-support, drill mechanism having a spindle co-operating with the support, screw-driver mechanism having a spindle co-operating with the support, each spindle being provided with rack-teeth, means for moving the support to present a shoe upon it to either the drill mechanism or the screw-driver mechanism, means for rotating each spindle, two levers fulcrumed side by side, means for oscillating the levers, two aligned shafts, gearing connecting the levers to the respective shafts, a gear rotatable about each shaft and meshing with the rack-teeth of one of the spindles, and a torsion-spring joining the gear to its shaft.

77. In a heel-attaching machine, a shoe-support, drill mechanism having a spindle co-operating with the support, screw-driver mechanism having a spindle co-operating with the support, each spindle being provided with rack-teeth, means for moving the support to present a shoe upon it to either the drill mechanism or the screw-driver mechanism, means for rotating each spindle, two levers fulcrumed side by side, a cylinder provided with cam-grooves in its opposite faces and acting upon the respective levers, two aligned shafts, gearing connecting the levers to the respective shafts, a gear rotatable about each shaft and meshing with the rack-teeth of one of the spindles, and a torsion-spring joining the gear to its shaft.

78. In a machine for operating through passages in lasts within shoes, a fastening-inserting member movable toward and from the last-passage, fastening-engaging members situated at opposite sides of the inserting member, and means for separating the engaging members to permit the application of a fastening to the inserting member and for closing said engaging members to align the applied fastening with the last-passage.

79. In a machine for operating through passages in lasts within shoes, a fastening-inserting member movable toward and from the last-passage, fastening-engaging members situated at opposite sides of the inserting member, means for separating the engaging members to permit the application of a fastening to the inserting member and for closing said engaging members to align the applied fastening with the last-passage, and again separating the engaging members only after a portion of the fastening is within the last-passage.

80. In a heel-attaching machine, a screw-inserting mechanism comprising a rotary and reciprocatory screw-driver, screw-engaging members situated at opposite sides of the driver, and means for separating the members to permit the application of a screw to the driver and for closing the members to align the applied screw with the driver.

81. In a heel-attaching machine, a screw-inserting mechanism comprising a rotary and reciprocatory screw-driver, screw-engaging members situated at opposite sides of the driver, means for separating the members to permit the application of a screw to the driver and for closing the members to align the applied screw with the driver, and means for reciprocating the screw-driver to advance the aligned screw into co-operation with the work before the members are separated.

82. In a heel-attaching machine, a screw-inserting mechanism comprising a rotary and reciprocating screw-driver, screw-engaging members situated at opposite sides of the driver, means for separating the members to permit the application of a screw to the driver and for closing the members to aline the applied screw with the driver, and means for reciprocating the screw-driver to advance the alined screw into co-operation with the work before the members are separated, there being inclined surfaces upon the members with which the screw may contact in its advance.

83. In a heel-attaching machine, a screw-inserting mechanism comprising a rotary and reciprocating screw-driver, screw-engaging members situated at opposite sides of the driver, means for separating the members to permit the application of a screw to the driver and for closing the members to aline the applied screw with the driver, and means for reciprocating the screw-driver to insert the screw while the members are separated.

84. In a heel-attaching machine, a screw-inserting mechanism comprising a rotary and reciprocating screw-driver, screw-engaging members situated at opposite sides of the driver, and means for separating the members to permit the application of a screw to the driver and for closing the members to aline the applied screw with the driver, said driver being provided with means for holding the screw in preparation for its alinement.

85. In a heel-attaching machine, a shoe-support, a rotary spindle, a screw-receiving chuck 35

upon the spindle, means for reciprocating the spindle to carry the chuck toward and from the support, screw-engaging fingers pivoted at opposite sides of the chuck, and means for separating the fingers when the chuck is raised to the support and closing the fingers when the chuck is lowered from the support.

86. In a heel-attaching machine, a shoe-support, a rotary spindle, a screw-receiving chuck carried by the spindle, a guide for the spindle, means for reciprocating the spindle in the guide, screw-engaging fingers pivoted upon the guide, and means for turning the fingers upon their pivots for the reception of a screw by the chuck and for its alinement and insertion.

87. In a heel-attaching machine, a shoe-support, a rotary spindle, a screw-receiving chuck upon the spindle, means for reciprocating the spindle to carry the chuck toward and from the support, screw-engaging fingers pivoted at opposite sides of the chuck, an arm extending from each finger, a rotatable cam, and means acted upon by the cam and connected to the arms for oscillating the fingers.

88. In a heel-attaching machine, a shoe-support, a rotary spindle, a screw-receiving chuck upon the spindle, means for reciprocating the spindle to carry the chuck toward and from the support, screw-engaging fingers pivoted at opposite sides of the chuck, an arm extending from each finger, there being a projection from one arm movable in a slot in the other, a rod fixed to one of the arms, and means for reciprocating the rod.

JOHN T. LANCASTER.

DISCLAIMER

2,293,834.—*John T. Lancaster*, Newton, Mass. FASTENING-INSERTING MACHINE. Patent dated August 25, 1942. Disclaimer filed January 27, 1945, by the assignee, *United Shoe Machinery Corporation*.

Hereby enters this disclaimer to claims 5 and 7 of said Letters Patent.
